Fig. 4.

FIG. 1 is a perspective view of a carboy embodying my new design;

FIG. 2 is a top plan view thereof;

FIG. 3 is a side elevational view thereof; and

FIG. 4 is a bottom plan view thereof.

The characteristic features of my design reside in the combination of a carboy of the configuration shown with a concave central circular portion in the top divided by an upstanding solid partition, intersected by a curved handle, and recesses outside of said concave central portion and positioned adjacent the ends of said handle.

I claim:

The ornamental design for a carboy, substantially as shown and described.
